UNITED STATES PATENT OFFICE.

FRANK E. KENNEY, OF ST. PAUL, MINNESOTA, ASSIGNOR OF ONE-HALF TO
DANIEL N. NESTER, OF SAME PLACE.

APPARATUS FOR PURIFYING FEED-WATER.

SPECIFICATION forming part of Letters Patent No. 558,188, dated April 14, 1896.

Application filed January 16, 1896. Serial No. 575,697. (No model.)

To all whom it may concern:

Be it known that I, FRANK E. KENNEY, a citizen of the United States, residing at St. Paul, in the county of Ramsey and State of Minnesota, have invented certain new and useful Improvements in Apparatus for Separating Alkali, &c., from Water; and I do hereby declare the following to be a full, clear, and exact description of the invention, such as will enable others skilled in the art to which it appertains to make and use the same.

My invention has for its object to provide an improved apparatus for separating foreign materials from water containing the same in solution or suspension.

The invention is especially designed for separating alkali from alkaline water, so as to render it possible to obtain pure feed-water for boilers in those sections of country, like the far Northwest, wherein water in its natural condition is so thoroughly impregnated with alkali as to be extremely objectionable for boiler use.

To these ends my invention consists of the novel apparatus which will be hereinafter fully described, and defined in the claims.

The invention is illustrated in the accompanying drawings, wherein like notations refer to like parts throughout the several views.

Figure 1 is a view chiefly in side elevation, but partly in vertical section, with some portions broken away, illustrating a return-flue boiler as equipped with my improved apparatus or separator. Fig. 2 is a detail in sectional perspective showing the supply-distributer of the separator detached. Fig. 3 is a detail in longitudinal vertical section through part of the steam-cage of the separator detached. Fig. 4 is a detail in sectional perspective of the purified feed-water collector of the separator detached. Fig. 5 is a vertical cross-section looking inward on the line $x' x'$ of Fig. 1. Fig. 6 is a perspective view of the entire separator detached from the boiler with some parts broken away and others shown in section; and Fig. 7 is a view of the front end of a straight-flue boiler, partly in side elevation and partly in vertical section, with some portions broken away, as

the same would appear when equipped with my separator.

In respect to the process used I have found by actual experience that by subjecting alkaline water to heat and steam the alkali can be concentrated and precipitated, so as to permit pure water to be drawn off from the top of the vessel in which the separation is effected. The alkali-laden water also frequently contains magnesia, lime, and various other ingredients held in solution. By the conjoint application of heat and steam I have found that all these ingredients, as well as the alkali, may be separated or removed. In carrying out the process the water is first heated to set free the alkali or other materials and then the steam is applied directly to the hottest portion of the body of water. The alkali and other materials set free by the heat tend to come to the surface in the form of a creamy-like foam, and when the free steam is applied directly thereto a churning action is set up, which has the effect of concentrating the alkali and other materials, such as magnesia and lime, into a solid form, which will then fall by gravity to the bottom of the receptacle in which the water is receiving treatment.

The exact action of the process will be more fully understood from the description of the apparatus for carrying the same into effect, which will now be given.

Considering first the application of my separator to the return-flue boiler, as shown in Fig. 1, the numeral 1 represents the boiler-shell proper; 2 the main flue, 3 the front-end extension, 4 the return-flue, 5 the stack, and 6 the steam-dome, all of the ordinary standard construction. My separator is designed for location in the front-end extension 3 of the boiler and has flues for coöperation with the boiler-flues for subjecting the water therein to the heating action. The separator-casing is preferably in the form of a drum-like receptacle made up of two segments $a a'$ of unequal size, with the larger thereof located below and the smaller above. The said drum-segments $a a'$ are flanged at their meeting joint, and are rigidly connected, so as to be separable at will, by means of tap-screws 100

- a*² or other suitable devices applied to the said flanges. The drum-segments are provided with suitable thimbles *a*³, extending lengthwise thereof, and through the said 5 thimbles extend stay-bolts *a*⁴, projecting from the front flue-sheet and engaged by nuts *a*⁵ at their outer ends. This construction serves to removably hold the separator in its proper working position in respect to the boiler.
- 10 The lower segment *a* of the separator-drum is provided with a series of flues corresponding to the boiler-flues in size and relative location, with their rear ends extending beyond the rear head of the drum and adapted to 15 enter the front ends of the boiler-flues with a telescoping action, so as to coöperate therewith. The separator for the return-flue boiler, for example, is provided in its lower segment *a* with a large flue *a*⁶, which coöperates with 20 the main flue 2 of the boiler to form a forward extension of the same, and is also provided with a series of small flues *a*⁷, which coöperate with the small or return flues 4 of 25 the boiler, as clearly shown in Figs. 1, 5, and 6.
- 25 The upper segment *a*' of the separator-drum is provided with a sectional cross-partition *a*⁸, having half-cylinder joint-flanges at its inner or meeting ends, which embrace a plugged pipe *a*⁹, and are rigidly united by tap-screws 30 *a*¹⁰ or other suitable means, and when so united the partition-flanges and said pipe *a*⁹ coöperate to form a hollow central section in the said partition, which is perforated on its upper and lower median lines, as shown at *a*¹¹ 35 and *a*¹² in Figs. 1 and 3. Within the said hollow or cylindrical central section of said partition *a*⁸ is located the discharge-section *b* of a steam-supply pipe *b* *b*', shown as tapping the steam-dome 6, and provided with a suitable 40 reduction-valve *b*². The discharge-section *b* of said steam-pipe is provided with perforations *b*³ on its lower median line only, so as to discharge the steam downward in small jets.
- 45 With the construction just described it is obvious that when the drum-segments *a* *a*' are united into working position, as shown in Figs. 1, 5, and 6, for example, the said partition formed by the parts *a*⁸ and *a*⁹ serves to 50 divide the separator-drum into two compartments, constituting chambers or receptacles at different levels, which only communicate with each other through the perforated partition-section *a*⁹. The said perforated cylindrical partition-section *a*⁹, on account of its 55 function, may hereinafter for convenience be called the "steam-cage." In the lower compartment of the separator is located a distributor *c*, having supply connections *c*' for the supply of the unpurified or crude water thereto. The said distributor *c* has a perforated bottom, as shown at *c*² in Figs. 1, 2, and 5, which construction causes the said distributor to 60 deliver the water downward in finely-divided jets.
- 65 A collector *f* is located in the upper compartment and is provided with an outflow or

discharge pipe *f*', leading to the boiler for supplying the purified water thereto. The outflow-pipe *f*' is provided with a suitable check-valve *f*². The collector *f* is shown as in the form of a hollow casting with foot-piece or pedestal *f*³ resting on the partition-plate *a*⁸ and secured thereto by tap-screw *f*⁴. The said collector *f* is provided with perforations *f*⁵ in its top wall, so as to receive the water from above downward. The separator is also provided with a top pipe *g*, rising from the upper segment *a*' and projecting through the shell of the front-end extension, and to this 80 pipe *g* is applied an ordinary safety-valve *g*'. The lower segment *a* of the separator is provided with a blow-off pipe *h*, extending downward through the wall of the front-end extension and provided with lateral extensions *h*', which may be of a size to serve as a mud-drum and are equipped with valved outlets *h*² for the discharge of the material therefrom.

Operation: Having regard to the action, it 90 is obvious from the description of the parts so far given that the separator as an entirety will be subjected to the heat in the front-end extension of the boiler and that the lower or flue segment *a* of the separator-drum will be 95 subjected to the same advantageous application of the heat as the boiler itself, or perhaps even better on account of the separator-flues *a*⁶ and *a*⁷. Hence the unpurified water supplied to the lower compartment of the 100 separator through the distributor *c* will be rapidly heated and the hotter portions of the same will rise and flow through the steam-cage *a*⁹ into the upper compartment, and thence through the collector *f* and the pipe *f*' to the boiler. As the unpurified water becomes heated in the lower compartment of the separator, the alkali, magnesia, lime, &c., but especially the alkali, will be set free and tend to come to the top and collect thereon 110 in the form of a cream-like foam; but the said foam is met at the steam-cage *a*⁹ or the only available passage-way into the upper compartment by the jets of steam supplied from the pipe *b* *b*'. As the discharge of the 115 steam from the steam-pipe *b* *b*' is downward, the greater portion of the same passes through the lower perforations *a*¹¹ of the cage *a*⁹ and into the lower compartment. These jets of steam meeting the foam at the entrance to 120 the cage blow or drive the same back into the lower compartment, leaving a clear way for the water to enter the cage, and has the further effect of setting up a churning action in the lower compartment which concentrates the alkali and other materials into 125 solid form, so that the same will collect by gravity at the bottom of the lower compartment or in the mud-drum below the same. In this way only the pure water will pass into 130 the upper compartment of the separator and flow thence into the boiler or other receptacle through the collector *f* and the outflow-pipe *f*'.

The location and form of the distributor *c*,

arranged to discharge downward in finely divided jets, are an advantage for the supply of the unpurified water to the separator, inasmuch as thereby violent agitation from the inflow at the bottom of the lower compartment is avoided and chance is afforded for the precipitation of materials, such as mud, &c., held in suspension. The churning action due to the effect of the steam on the foam in the lower compartment is of course confined chiefly to the upper or hottest layers of the water and may be regulated so as not to be sufficient to violently agitate the lowest layers of the water and interfere with the collecting action of the precipitates.

The application of the separator to a straight-flue boiler is shown in Fig. 7, and the construction and operation are substantially the same as in the form already considered, 20 with the single exception of the difference in the form of the flues in the separator, which are all small flues t for coöperation with the flues 4^a of the straight-flue boiler.

It should be further noted that the construction of the separator permits the same to be readily taken down and removed from the boiler or the upper segment of the drum to be removed for inspection or cleaning out of the lower segment while in working position. 25 The upper segment is also provided with a hand-hole closed by the ordinary cover p , as best shown in Figs. 1 and 6, which permits access to the interior of the upper segment at will while in working position. The flues of the separator are also of such character and so applied as to permit the same to be readily removed and replaced by new flues whenever so desired.

It should also be noted that the reduction- 40 valve b^2 in the steam-supply pipe b b' for the separator enables the steam to be delivered on the separator side at any desired constant pressure regardless of the steam-pressure in the boiler.

Although my invention has been herein illustrated as applied for purifying the feed-water for steam-boilers, it will be understood that the same might be used for purifying water designed for any other desired use. 45 The boiler application, however, is of great importance and utility, because the trouble from alkali water is such an extremely serious one in the alkali districts—such, for example, as in northern Minnesota, the two Dakotas, 50 Nebraska, and many of the Northwestern States. The alkaline deposits are much more injurious to boilers than lime deposits, for example, because of the greater corroding action thereof on the metal. It is also extremely ob- 55 jectionable on account of the foaming in the boiler. Hitherto, so far as I am aware, no satisfactory separator has been available for removing the alkali. By actual experience I have demonstrated that my invention herein 60 disclosed will do the work, thereby rendering pure water available, and greatly adding to

the life and safety of steam-boilers, besides the advantages of pure water for other uses.

It will be understood, of course, that minor details of the construction might be changed 70 without departing from the spirit of my invention.

What I claim, and desire to secure by Letters Patent of the United States, is as follows:

1. A water-separator, comprising a pair of receptacles or compartments, at different levels, a steam-cage constituting or forming a part of the passage connecting said compartments, and provided with a supply of steam discharging therethrough into the lower compartment, means for heating the said lower receptacle or compartment or the water therein, supply connections to said lower compartment, and outflow or discharge connections from said upper compartment, substantially 80 as described.

2. A water-separator, comprising a receptacle divided by a cross-partition, into lower and upper compartments and having a steam-cage forming a part of said cross-partition, a 90 discharge-section of steam-supply pipe, located in said cage and discharging downward therethrough into the lower compartment, supply connections to said lower compartment, outflow connections from said 95 upper compartment and means for heating said lower compartment, substantially as described.

3. A water-separator, comprising a receptacle divided, by a cross-partition, into a lower 100 and an upper compartment, a steam-cage, in said partition, serving to connect said compartments, a discharge-section of steam-pipe in said cage, discharging downward, there- 105 through into said lower compartment, a distributor in said lower compartment, receiving the unpurified water and discharging the same downward, means for heating said lower compartment, and outflow connections from said upper compartment, substantially as de- 110 scribed.

4. A water-separator, comprising a receptacle divided, by a cross-partition, into lower and upper compartments, a steam-cage in said partition, serving to connect said compartments, a discharge-section of steam-supply pipe, located in said cage and discharging downward therethrough, into the lower compartment, means for heating said lower compartment, a distributor, in said lower com- 115 partment, receiving the unpurified water and discharging the same downward into said compartment, and a collector, in said upper compartment, receiving from above down- 120 ward and provided with outflow or discharge 125 connections, substantially as described.

5. The combination with a steam-boiler, having a front-end extension, of a feed-water heater and separator, located therein, and comprising a receptacle, divided by a cross- 130 partition into lower and upper compartments, the lower member of which is provided with

- flue-sections matching and forming continuations of the boiler-flues, a steam-cage, in said partition, connecting said compartments, a discharge-section of steam-pipe in said cage discharging downward therethrough into, 5 lower compartment, supply connections to said lower compartment, and outflow connections from said upper compartment to the boiler, substantially as described.
6. The combination with a steam-boiler, having a front-end extension, of a combined feed-water heater and separator, located therein, comprising a receptacle divided, by a cross-partition, into lower and upper compartments, the lower member of which is provided with flue-sections matching and forming continuations of the boiler-flues, a steam-cage in said partition connecting said compartments, a steam-pipe, from the boiler, having a discharge-section thereof within said cage, discharging downward therethrough into the lower compartment, a reduction-valve in said steam-pipe, supply connections to said lower compartment, and outflow connections from said upper compartment to the boiler, substantially as described.
7. The combination with a steam-boiler having a front-end extension of the combined feed-water heater and separator, located therein, comprising a receptacle, divided by a cross-partition into lower and upper com-

partments, the lower member of which is provided with flues matching and coöperating with the boiler-flues, a steam-cage in said partition, connecting said compartments, a 35 steam-supply pipe having its discharge-section in said cage and discharging downward therethrough into the lower compartment, a reduction-valve in said steam-supply pipe, a distributor, in said lower compartment, with 40 discharge-openings in its bottom and having supply connections for the unpurified water, and a collector, in said upper compartment, provided with receiving-openings in its top and having outlet connections leading to the 45 boiler, all substantially as and for the purpose set forth.

8. The combination with a boiler having a front-end extension, of the drum-like receptacle, adapted to serve as a feed-water heater 50 and separator, composed of the flanged lower and upper segments *a a'*, separably connected together, at their joint-flanges, and provided with thimbles engaged by nutted stay-bolts projecting from the front flue-sheet of the 55 boiler, substantially as described.

In testimony whereof I affix my signature in presence of two witnesses.

FRANK E. KENNEY.
